BOAT UPPER SHELL

Kenneth R. Baker, Anderson, Ronald E. Plescia, San Jose,
and Gary C. Ferguson, Redding, Calif., assignors to
Saul Davidson, Denver, Colo.

Filed Sept. 24, 1971, Ser. No. 183,720

Term of patent 14 years

Int. Cl. D12—06

U.S. Cl. D71—1 S

FIG 1

FIG 2

FIG.3

FIG.4

FIG 5

FIG 6

FIG 7

FIG. 1 is a perspective of the boat upper shell design of this invention showing a boat hull in broken lines for illustrative purposes only;

FIG. 2 is a plan view thereof;

FIG. 3 is a perspective view of the boat upper shell design with the hatch cover removed;

FIG. 4 is a plan view thereof;

FIG. 5 is a side elevational view thereof, the other side being substantially a mirror image thereof;

FIG. 6 is a front elevational view thereof;

FIG. 7 is a back view thereof.

We claim:

The ornamental design for a boat upper shell, as shown and described.
